(57) CLAIM

The ornamental design for a dental flosser as shown and described.

DESCRIPTION

FIG. 1 is a front view of a dental flosser showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a front perspective view thereof; and,

FIG. 8 is a rear perspective view thereof.

The broken lines in the FIGURES depict portions of the dental flosser that form no part of the claimed design.
